UNITED STATES PATENT OFFICE.

HARVEY E. REX, OF SAN FRANCISCO, CALIFORNIA.

RAZOR STROP.

Application filed August 24, 1921. Serial No. 494,928.

To all whom it may concern:

Be it known that I, HARVEY E. REX, a citizen of the United States, and resident of San Francisco, county of San Francisco, 5 and State of California, have invented a new and useful Razor Strop, of which the following is a specification.

My invention relates in general to razor strops of the type commonly used for sharpening straight razors and has reference more particularly to a combination strop and razor holder in which an improved handle is so arranged that the strop may be folded upon itself to form a pocket for holding 15 the razor, and with the folds clamped in such position by the handle.

The primary object of my invention is to provide a device as above identified which is simple to operate, cheap to manufacture 20 and capable of performing its intended use with the greatest efficiency.

The invention possesses further features which will be set forth at length in the following description of the accompanying 25 drawing, in which I have illustrated the preferred form of the device. In said drawing, Figure 1 is a perspective view of the strop as folded to form the holder, and Figure 2 is a perspective view of the strop 30 as hung from a hook for the purpose of sharpening the razor.

Referring now to the drawing in detail, "A" represents the strop per se which may be made from either a strip or plurality of 35 strips of leather or other material or a combination of leather and other material, with the handle "B" thereof attached to the strop at one end thereof, as best shown in Figure 2. In referring to the part "B" as a handle, 40 it is of course understood that it may be also used as a means for hanging the strop from a hook, however, the position of the strop on the hook may be reversed so that it is hung from the gromet "C" with the handle 45 grasped by the hand for holding the strop substantially taut.

The handle embodies in its construction a pair of separate loops (5) and (6), the loop (5) having a transverse straight end (7) 50 adapted to be attached to the strop across the end thereof by folding the end of the strop over the end and sewing or otherwise fastening the fold, as at (8). The loop (6) of the handle is made with a pair of spaced 55 eye hooks (9) through which the transverse straight end (7) of the loop (5) passes and

with the fold (8) of the strop slipped, as shown, to enable the eyes to be engaged by the end (7). The loops are of substantially the same length and in making up the holder 60 for the razor, which is shown as at "D" in Figure 1, the strop is folded once upon itself to leave the end "E" terminating short of the opposite end, as best shown in Figure 1, so as to make a pocket for the razor "D" 65 between the folds. The strop is maintained folded by the loops (5) and (6) of the handle which are turned to longitudinally overlie opposite sides of the folds, as shown in Figure 1, with link catches (10) and (11) 70 carried by one of the loops and adapted to extend across the thickness of the strop folds at the side edges thereof and engage the other loop on the opposite side of the strop folds, as best shown in Figure 1. These link 75 catches may be made of spring metal so that they may be sprung in place and also hold the folds of the strop clamped between the loops under tension.

A shaving brush, shown as at "F," may be 80 conveniently carried by the holder at the closed ends of the folds, as shown in Figure 1.

In the case of a very long strop, or in other instances which require it, the strop 85 per se may be folded a number of times upon itself to make up a plurality of pockets, in which event the link catches (10) and (11) would necessarily have to be of a length to accommodate the added thickness of the 90 folds in order that they would extend across the side edges thereof for engaging both the handle loops.

My invention is especially adapted for use in carrying straight razors and a strop for 95 sharpening them in a neat and compact manner, thus overcoming the disadvantage of packing a straight razor with the strop and brush in the heretofore inconvenient manner.

I claim:

1. In a device of the class described, a 100 razor sharpening strop, a two-part handle at one end of the strop, the two parts of the handle being separable and the strop adapted to be folded upon itself with the handle longitudinally overlying opposite sides of the strop folds and means holding the handle in said position with the strop folds clamped therebetween, comprising link catches fixed 105 to one of the handle parts on one side of the strop folds adapted to extend across the 110

thickness of the strop folds at the side edges thereof and engage the other part of the handle on the opposite side of said folds.

2. In a device of the class described, a 5 razor sharpening strop, a handle therefor, comprising separate looped members, one of said members having a transverse straight end adapted to be attached to the strop across the end thereof, the other member of said 10 handle having eye hooks through which said transverse straight end passes, the strop adapted to be folded upon itself with the two members of the handle turned to longitudinally overlie opposite sides of the folds, 15 and means for holding the handle in said position with the strop folds clamped therebetween.

3. In a device of the class described, a 20 razor sharpening strop, a handle therefor, comprising separate looped members, one of said members having a transverse straight end adapted to be attached to the strop across the end thereof, the other member of said 25 handle having eye hooks through which said transverse straight end passes, the strop adapted to be folded upon itself with the two members of the handle turned to longitudinally overlie opposite sides of

the folds, and means for holding the handle in said position with the strop folds 30 clamped therebetween, comprising means carried by the handle member on one side of the strop folds adapted to engage the handle member on the opposite side of the strop folds. 35

4. In a device of the class described, a razor sharpening strop, a handle therefor, said handle comprising separate looped members, one of said members having a 40 transverse straight end adapted to be attached to the strop across the end thereof, said other member having eye hooks through which said transverse straight end passes, the strop adapted to be folded upon itself with the two handle members turned to 45 longitudinally overlie opposite sides of the strop folds, means for holding the handle in said position with the strop folds clamped therebetween, comprising link catches fixed to the handle member on one side of the 50 strop folds adapted to extend across the thickness of the strop folds at the side edges thereof and engage the other handle member on the opposite side of the strop folds.

HARVEY E. REX.
